UNITED STATES PATENT OFFICE.

CHRISTIAN L. SCHNEIDER, OF DAVENPORT, IOWA.

SASH-WEIGHT SUPPORT.

Application filed June 15, 1925. Serial No. 37,066.

The present invention relates to supports for window sashes, or like and similar objects.

In windows having movable sashes, particularly of the sliding sash type, it is not always possible to construct the sashes so that they will be counterbalanced equally by the weights usually used as window weights. Moreover, more or less friction between the sashes and the window casings will result in more or less resistance to the raising and lowering of the sashes. In constructions where each sash is connected to individual weights at each side thereof as well as in constructions where the two sashes of the window are connected together by a connector, such as a rope or chain, passing over a pair of casing pulleys and through a pulley of a common weight, it is usually found that there is not an equalization of the weights of the parts, such as the sashes and the window weights. These have a disadvantage of requiring that the window weights be variable, or, that some other means be used to counterbalance or equalize the difference in the weights of the objects or counteract their unbalanced effect, and particularly so in the case where the two sashes are connected together by a common connector passing through a common weight.

The present invention is designed and adapted to avoid these disadvantages and has among its objects, the provision of counteracting devices for counteracting or equalizing the differences of weights between a window sash and a window weight, or between two window sashes having a common window weight; to provide means for applying resistance to the connector portion connected to the heavier object, whether it be a sash, a window weight, or similar objects; to provide for bending or kinking the connector for imposing such resistance thereto; to provide for varying or adjusting the amount of bending or kinking of the connector, and hence, the resistance to the overweight of the heavier object; to provide for, preferably, bending the connector between a sheave or pulley, over which the connector runs, and an idler carried near the sheave or pulley; to provide for a movable member, such as a sliding yoke, preferably carrying a bending roller, and an operating element, such as a rotating screw for effecting the sliding of the yoke when the screw is rotated; to provide for means, such

as a stop member, preferably in the form of a cross-pin for limiting the movement of the yoke in one direction, whereby the screw and the yoke will not become disconnected from each other; the yoke preferably having a shoulder for engagement with the pin; to provide for mounting the screw, which preferably has a head, for rotary action, and means for holding the screw against longitudinal action and preventing it from working loose or becoming disconnected from the device, preferably by a part of a device overlapping the edge or border of the screw-head; and to provide for such other objects, advantages and capabilities as will later appear and are inherently possessed by the invention.

Referring to the drawings illustrating one form of the invention,

Figure 1 is a view in perspective of a device constructed in accordance with the invention.

Figure 2 is a longitudinal sectional view through such device.

Figure 3 is a transverse sectional view taken on a plane represented by line 3—3 in Figure 2 of the drawings; and

Figure 4 is a fragmentary sectional view taken on a plane represented by line 4—4 of Figure 3.

Referring now more in detail to the drawings, an embodiment selected to illustrate the invention is shown as comprising a supporting member 1 in the form of a casing or shell capable of being secured to a window casing or frame 2 by a suitable securing element, such as screws 3 passing through a face flange 4 forming, preferably, an integral part of the supporting member 1. Within the shell 1 is rotatably mounted a sheave or pulley 5 suitably grooved for the passage thereover of a flexible connector 6, such as a rope, chain or the like.

The side walls of the shell have depending portions 8 between which extends and to which is secured a shaft or pin 9 for rotatably supporting an idler roller 10 suitably grooved for the running thereover of the connector 6. Between the pulley 5 and the roller 10 is slidably supported a yoke 11 in tracks or channels 12 formed in the side walls of the shell 1. At the outer end of the yoke 11 is secured a shaft or pin 13 upon which is rotatably carried a bending or kinking roller 14 also suitably grooved for the running thereover of the connector 6.

At the other end of the yoke is provided a cross-head 15 apertured and threaded to receive the threaded part of a screw 16 having its unthreaded shank portion rotatably mounted in a bearing portion 17 integrally provided between the side walls of the shell 1 and at the front thereof and beneath the pulley 5. The screw preferably has a substantially cylindrical head 18 capable of 10 free rotation in a recess provided in the bearing portion 17 and at the front of the shell 1. The cross head also has a projecting portion 19 to provide a shoulder 20 capable of engaging with a cross pin 21 extending 15 between and secured to the side walls of the shell 1 and at a place to prevent the total disengagement of the cross head 15 from the end of the screw 16 when the yoke has been moved by this screw toward the rear of the 20 device.

Over the front or face portion of the device is preferably secured a face plate 22 by means of pins 23 driven into the flange portion 4 as clearly shown in Figure 2 of the drawings. The plate 22 preferably has suitable counter-sunk openings for the reception of the heads of the screws 3. It also has an elongated opening 24 out of which the pulley 5 and through which the rope 6 25 may pass to a weight (not shown). It also is provided with an aperture or opening 26 opposite the screw head 18, through which opening the end of a screw driver may pass for engagement with the slot of the screw 30 head 18 for rotating the screw when it is desired to adjust or vary the yoke 11 and the roller 14. The aperture 26 is preferably smaller than the diameter of the head 18 so as to provide an overlapping portion over 35 the edge or border of the head 18 so as to prevent the longitudinal movement of the screw, when the same is rotated, and also the working loose or falling apart of the screw 40 from the device.

45 The rope 6, or similar connector, passes over the pulley 5 and in front of the roller 14 and behind the roller 10 with its end portion 27 extending and connected to a weight or a pulley carried by a weight in a case 50 where the rope continues upwardly to a second supporting device and to a second window sash. The other end 28 of this rope extends and is connected to a window sash.

In operation the rope portion extending 55 to the sash passes over the main pulley 5 under pulley 14 and over pulley 10, the rope being bent more or less by a movement of the pulley 14 so as to kink or crowd that portion of the rope between the rollers 10 and 14, so as to impose more or less resistance to the pull or tension on the rope so as to counteract the difference of weights of the sash and the window weight and thus avoiding undesired motion therebetween.

60 The amount of bend made in the rope is

varied by a sliding or longitudinal movement of the yoke effected by a rotation of the screw 16. It will be clear that when the screw is operated in one direction the yoke will be fed or moved outwardly and when rotated in an opposite direction it will be fed inwardly or towards the front so as to increase the bend or kink in the rope. This bends or crowds the rope portion between the rollers so that it will be more difficult for the rope to pass over the main pulley 5, that is, it will take greater effort for the weight to pull on the rope portion 27 and will have less lifting effect on the sash connected to the rope portion 28.

70 In order that the yoke may not be fed to the rear too far so that the end of the screw would become detached from the cross head, the shoulder 20 will contact with the stop or limiting pin 21 to prevent this.

75 While I have herein described and upon the drawings shown an illustrative embodiment of the invention, it is to be understood that the invention comprehends other constructions, details, and arrangements of parts than those shown and described, without departing from the spirit thereof.

80 Having thus described my invention, I claim:

1. In sash weight supports, in combination, an idler pulley mounted on a yoke, said yoke being slidably adjustable between fixed limits, a plurality of pulleys rotatable by a flexible means having a bend, said bend being variable by said adjustable pulley.

90 2. In sash weight supports, in combination, a threaded yoke slidable on a supporting member, said yoke being adjustable and operable by a non-translatable threaded member, an idler pulley mounted in said yoke and engaging a flexible connector, other pulleys engaging said flexible connector, whereby a bend is made in said connector to create a drag between said pulleys and sash weights.

95 3. A sash support having a shell for attachment to a window casing, a sheave rotatably carried by the shell and over which passes a flexible connector to the sash and to a weight, a roller over which passes the connector from the weight to the sheave, a second roller located on the opposite side of the connector from the sheave and first mentioned roller, an adjustable carrier for the second roller for causing the connector to be more or less tortuous and constrained between the rollers, a tool operated element connected to the carrier and operable to adjust the position of the carrier and second roller relative to the first roller, and means guarding against the disassembling of the elements.

100 4. In sash weight supports, in combination, an enclosed bracket, a plurality of pulleys therein engaging a flexible connector,

95

100

105

110

115

120

125

130

one of said pulleys being slidably adjustable by self limiting threaded means, whereby the said connector is kinked, causing a drag on the rotary means.

5 5. In a device of the character disclosed, a rotatable sheave for a flexible connector running from a sash to a weight, means for bending the connector to offer resistance to the difference in weights of the sash and

10 window weight, said means including a slid-

ing yoke and a pulley for engaging the connector to bend it more or less, a screw threaded to the yoke and rotatable to slide the yoke to and fro, and a stop element for limiting the sliding of the yoke to prevent

15

the disconnection of the screw and yoke.

In witness whereof, I hereunto subscribe my name to this specification.

CHRISTIAN L. SCHNEIDER.
